DISPLAY CARTON

Henry K. Powell, Chicago, Ill., assignor to Morris
Paper Mills, Chicago, Ill., a corporation of
Illinois

Application April 16, 1934, Serial No. 720,696

3 Claims. (Cl. 206—44)

The present invention pertains to cartons constructed of fibrous material such as cardboard and has particular reference to an improvement in cartons of the type adapted for displaying merchandise.

5 A principal object of the invention is to provide an effective display device for use in connection with cartons.

An additional object is the provision of a 10 fibrous carton or container having a top portion or cover for protecting merchandise, which cover may be folded into the form of a particularly desirable display mechanism.

A still further object is to provide a carton 15 having a display device which may be used on a counter or shelf without hiding other merchandise adjacent the carton.

A further object is to provide a carton having 20 a triangular display device which may contain advertising matter or even merchandise itself in such a manner as to present the advertising matter or merchandise to the eye of the prospective customer at an advantageous angle.

These and other objects will be evident from 25 a consideration of the following illustrative and explanatory specification and by reference to the accompanying drawings, in which

Fig. 1 is a perspective view of a carton constructed in accordance with my invention and 30 having its cover portion in closed position;

Fig. 2 is a perspective view of the carton shown in Fig. 1 and shows the top or cover portion folded into the form of a display device;

Fig. 3 is a sectional view taken along line 3—3 35 of Fig. 2;

Fig. 4 is a sectional view taken along line 4—4 of Fig. 2 and in addition includes the showing of a modified form of the carton adapted for holding merchandise in the display device;

Fig. 5 is a sectional view taken along line 5—5 40 of Fig. 4;

Fig. 6 is a perspective view of a carton of a different type and having a cover foldable into the form of a display device in accordance with 45 my invention;

Fig. 7 is a view of the blank from which the carton shown in Figs. 1 to 5 is produced; and

Fig. 8 is a view of the blank from which the carton shown in Fig. 6 is produced.

50 Heretofore it has been recognized as advantageous to provide a carton operable to contain merchandise for shipping and storing purposes, and having a top or cover portion which may be folded into such a form as to enhance the display value of the carton when positioned on a shelf

or display case by the merchant. In some cases the cover is folded beneath the container to tilt the carton forwardly. Patent No. 1,685,606, issued September 25, 1928, discloses a carton of this type. It has also been the custom to provide the carton in many cases with a cover portion which may be folded upon itself to form an up-standing sheet upon which may be printed advertising matter such as pictures of merchandise to be displayed. A principal example of this 10 latter type of display container is described in Patent No. 1,513,318. In this patent it will be noted that the cover of the container is scored in its center and folded into the form of a backwardly extending display device. A particular 15 objection which has prevented cartons of this type from being properly commercialized is that the backwardly extending cover prevents the carton from being utilized on a more or less crowded shelf, due to the hiding of other merchandise 20 by the cover. Also, the backwardly extending cover was free to pivot about the score line which joins the cover to the rear wall of the carton, thereby causing the display device to be unstable. Often, the fixed angle at which the display device 25 presented advertising matter was not properly suited for the use to which the carton was put.

In accordance with my invention cartons of the type described are provided with a highly desirable display device by scoring the top or 30 cover of the carton along a plurality of transverse lines dividing the cover into sections, the rearmost of which is of less width than half the width of the carton. The free edge of the cover is provided with a locking flap, whereby the cover 35 may be folded into substantially triangular shape with the rearmost section in vertical position, the front and base sections of the triangle being biased, due to the resiliency of the material used, in such a way as to cause the rearmost section 40 and the rear wall of the carton with which the rear section is integrally connected to bulge outwardly. This bulging prevents the rear or vertical section of the display device from being folded backwardly beyond vertical position, 45 thereby affording a strong and rigid display device which may be used on a shelf upon which it is desired to display other merchandise and which, due to the angle of the legs of the triangle, displays the printed matter at a highly 50 advantageous angle.

As shown in Fig. 7, the carton is composed of a blank suitably cut, scored and folded to form a bottom 10, side walls 11 and 12, a front wall 13, and a rear wall 14. The rear wall has inte- 55

- grally connected thereto a top or cover member 15. Side wall 11 has an integral forwardly extending flap 16 provided with an opening 17 and side 12 has a similar flap 18 and opening 19.
- 8 To the free end of the front wall 13 is joined a closing flap 20 having an intermediate score line 21 and notches 22 along its free edge, it being understood that the opposing flap 20 is separated from the front wall by means of a score line 23.
- 10 Side wall 11 is also provided with a foldable flap 24 and side wall 12 is provided with a similar vertical flap 25, the function of these latter flaps to be described more particularly herein-after.
- 15 To the rear edge of side wall 11 is integrally secured a rear locking flap 26 which is cut along the line 27 in order to receive a complementary locking flap 28, the latter being integrally secured to side wall 12.
- 20 The cover member 15 is joined to the rear wall 14 along a score line 29. At the opposite end of the cover member is a locking flap 30 joined to the cover member along a score line 31. Intermediate the score lines 29 and 31 are provided additional transverse score lines 32 and 33, which divide the cover into a section 34 adjacent the cover-locking flap, an intermediate section 35, and an inner section 36 adjacent the rear wall. It will be noted that the section 36 is of less width than half the width of the carton.
- 25 To erect the carton the side walls 11 and 12 are rotated about the score lines by which they are integrally connected with the bottom member into substantially vertical position. Flaps 16 and 18 are then rotated toward each other and the front wall 13 is rotated upwardly in front of the flaps 16 and 18, the long flap 20 being then folded over flaps 16 and 18 and the notches 22 engaged into openings 17 and 19 to complete the setting up of the front portion of the carton. The rear wall 14 then is rotated upwardly into substantially vertical position and the flaps 26 and 28 are folded on the outside of the rear wall, the flap 28 being interlocked in cut 27 of the flap 26 to complete the erection of the carton.
- 30 To close the carton the flaps 24 and 25 are folded into horizontal position and the cover member 15 is rotated about score line 29 by which it is secured to the rear wall into horizontal position, the cover-locking flap 30 being pressed downwardly between the front ends of flaps 24 and 25 and the front wall. Before closing the cover it is customary to fill the carton with merchandise for shipping, storing or similar purposes.
- 35 When it is desired to use the carton for display purposes the flap 30 is released from engagement with the flaps 24 and 25 and the front wall, and the cover is bent into triangular shape by rotating sections 35 and 34 about score lines 32 and 33. The cover-locking strip 31 is rotated downwardly in a direction opposite to that of the rotation of sections 34 and 35 and the flap 30 is inserted between the rear ends of flaps 24 and 25 and the rear wall 14. When this operation has been completed the cover assumes the shape and position shown in Figs. 2, 3, 4 and 5. In such position it will be noted that the section 34, constituting the base of the triangle, engages the upper portion of flaps 24 and 25, maintaining them in down position and thereby preventing the release of flap 30.
- 40 The effectiveness of this embodiment of my improved display device is due to a considerable ex-

tent to the nature of the materials used. Cardboard or similar fibrous materials of the type used for cartons are resilient to a certain extent and have an elastic limit which if exceeded causes the fibres of the carton to break down. 5

The upstanding section 36 constituting the vertical leg of the triangle extends upwardly a distance less than half the width of the carton and the angle between this rear leg and the downwardly and forwardly extending intermediate leg 35 is 10 less than 90°. Also, the angle between the intermediate leg 35 and the base section 36 is less than 90°. The nature of cardboard is such that when bent along the score line it will tend to return to the last 90° position through which it was 15 turned or bent. Therefore, in the display device as shown in Fig. 2 the flap 30 tends to press the base portion outwardly and is held against such action by flaps 24 and 25. The base section 34 tends to straighten out along score line 32 and, 20 as the flap 30 is held against movement, the leg presses back against the vertical section 36 of the display device. The intermediate leg 35 tends to return to a position at right angles to the vertical section of the triangle and also produces 25 a backwardly pressing effect. The combination of the resilient effects of the triangular sections causes the entire rear wall 14 and the upstanding section 36 of the display device to assume a bowed or bulging shape, as shown in Figs. 4 and 5. 30 Rotation of the substantially vertical section 36 of the triangle about the score line to which it is joined to the rear wall 14 is prevented by this bulging of the rear wall.

In a preferred modification of the device, the 35 downwardly and forwardly extending intermediate section 35 is the widest of the triangular sections, and the base section 34 is the most narrow section of the device. In this modification the upper angle formed between the vertical sec- 40 tion and the intermediate section is more acute than the forward angle between the intermediate section and the base section.

In certain instances it is desirable to make a 45 more effective display of merchandise than can be obtained by the carton itself. In accordance with my invention, it is possible to provide the downwardly and forwardly extending intermediate section 35 with a cut-out portion 37, as shown in Fig. 4, which may be rotated about the 50 score line 32 to provide an opening in the triangular display device for reception of merchandise to be displayed. It will be understood that the merchandise to be displayed is positioned on top of the downwardly rotated section 37 and that the walls of the section 35 constitute a support for the merchandise. 55

The display device may be applied to cartons of the type in which stapling or other securing 60 methods are employed. In the modification of the display device as shown in Figs. 6 and 8, a blank is suitably cut, scored and folded to form bottom flaps 41, 42 and 43 secured respectively to a front wall 44, a side wall 45, a rear wall 46 and a 65 second side wall 47. Side walls 45 and 47 are provided with flaps 48 and 49 which function in the same manner as flaps 24 and 25 in the modification of the carton shown in Fig. 1. To the upper edge of rear wall 46 is attached an integral 70 cover member 50 of similar construction to the cover member 15. The cover 50 includes a vertical leg 51, a downwardly and forwardly extending intermediate leg 52, and a backwardly extending base leg 53, these various legs or sections 75

being separated by suitable score lines in the manner described heretofore with respect to the carton shown in Fig. 1. To the free end of base section 53 is attached a cover-locking flap 54 which is engaged between flaps 48 and 49 and the front wall 44 when the cover is in closed position. To set the carton up for display purposes, the cover is rotated into triangular shape about the score lines between the various sections and the flap 54 is locked between the flaps 48 and 49 in the rear wall. In this modification it will be noted that there is no supporting wall back of the rear wall 46, as is the case in the carton shown in Fig. 1. The action of the various sections of the triangular display mechanism shown in Figs. 6 and 8 causes the rear wall and vertical section 51 to bulge outwardly in the same manner as the modification described hereinbefore, thereby maintaining the display mechanism in rigid set-up condition.

Various modifications of the structure described hereinbefore are possible without departing from the scope of my invention. For instance, in certain cases it may be found desirable to employ a display device of the type described which is separate from the carton with which it is adapted to be used. In such cases, the substantially vertical rear section of the triangular display mechanism may be pressed inside the rear wall of the carton, as will be readily understood by one skilled in the art. This and all other such changes and variations in the structure described hereinbefore for purposes of ex-

planation are intended to be included in the appended claims.

I claim:

1. A display container of the type described, comprising a fibre body portion having a bottom, side walls, front and rear walls, a display member extending upwardly from the rear wall and composed of a fibre sheet adapted to form a cover for the container when in unfolded condition, said sheet being scored and folded into triangular 10 shape with a substantially vertical back section, a downwardly and inwardly extending front section, and a backwardly extending base section, a flap on the free end of said base section, and means for holding said flap adjacent the rear 15 wall, said back section and rear wall being in backwardly bowed shape.

2. A display container of the type described, comprising a fibre body portion having a rear wall bent into backwardly bowed shape, a rear top 20 section extending upwardly from said rear wall in backwardly bowed shape and forming one leg of a triangular display member, and other legs for said display member secured to said backwardly bowed rear top section. 25

3. A display container of the type described, comprising a fibrous body portion having a rear wall and a top section connected thereto along a score line, said top section being intermittently scored and folded under tension into display 30 shape with a vertical portion adjacent said rear wall holding the latter in outwardly bowed shape.

HENRY K. POWELL.
